US0D1057966S

(12) **United States Design Patent** (10) **Patent No.:** **US D1,057,966 S**
(45) **Date of Patent:** **** Jan. 14, 2025**

(54) **CERVICAL COLLAR FRONT ASSEMBLY**

(71) Applicant: **DeRoyal Industries, Inc.**, Powell, TN (US)

(72) Inventors: **Sarah O Davis**, Knoxville, TN (US); **Nicholas John Poker**, Knoxville, TN (US); **John Connor Brown**, Knoxville, TN (US); **Charles Joseph French, III**, Knoxville, TN (US); **Rebecca Laughon**, Powell, TN (US); **Dhanvin Sunil Desai**, Knoxville, TN (US); **Walter Cleveland Cowart**, Blaine, TN (US)

(73) Assignee: **DeRoyal Industries, Inc.**, Powell, TN (US)

(**) Term: **15 Years**

(21) Appl. No.: **29/883,451**

(22) Filed: **Jan. 30, 2023**

(51) LOC (15) Cl. **24-02**

(52) U.S. Cl.

USPC **D24/191**

(58) **Field of Classification Search**

USPC D24/155, 188, 189, 190, 191, 192, 200, D24/206, 209; D2/600, 602; D29/100, D29/101.1, 101.2

CPC .. A61F 5/055; A61F 5/05883; A61F 5/05891; A61F 5/02; A61F 13/128

CLAIM

The ornamental design for a cervical collar front assembly, as shown and described.

DESCRIPTION

FIG. 1 is a rear perspective view of a design of a cervical collar front assembly.

FIG. 2 is a right view of a design of a cervical collar front assembly.

FIG. 3 is a left view of a design of a cervical collar front assembly.

FIG. 4 is a top view of a design of a cervical collar front assembly.

FIG. 5 is a bottom view of a design of a cervical collar front assembly; and,

FIG. 6 is a front perspective view of a design of a cervical collar front assembly.

1 Claim, 6 Drawing Sheets
